UNITED STATES PATENT OFFICE.

JAKE BRADLEY, OF OAKLAND, CALIFORNIA, ASSIGNOR OF ONE-HALF TO C. E. PATTERSON, OF OAKLAND, CALIFORNIA.

DESIGN FOR A CIGARETTE HOLDER.

Application filed July 17, 1923. Serial No. 6,790. Term of patent 3½ years.

To all whom it may concern:

Be it known that I, JAKE BRADLEY, a citizen of the United States, residing at Oakland, in the county of Alameda and State of California, have invented a new, original, and ornamental Design for Cigarette Holder, of which the following is a specification, reference being had to the accompanying drawing, in which—

The figure is a perspective view of a cigarette holder, showing my new design.

The design comprises a mouthpiece as shown in connection with tubular netting having a semi-spherical closure at one end, said netting being provided with a plurality of circular bands extending around the circumference thereof and a plurality of longitudinal bands, preferably of metal, extending longitudinally thereof.

I claim:

The ornamental design for a cigarette holder, as shown.

In testimony whereof I affix my signature.

JAKE BRADLEY.
